TOY CLOWN

Gilbert Von Post Totten, Minneapolis, Minn.

Application September 8, 1954, Serial No. 32,196

Term of patent 3½ years

(Cl. D34—4)

Fig. 1 is a side elevational view of a toy clown showing my new design; and

Fig. 2 is a front elevational view thereof.

The broken lines appearing in Fig. 2 of the drawing are for illustrative purposes only.

I claim:

The ornamental design for a toy clown, substantially as shown and described.
